Primary Examiner — Sandra Snapp(74) *Attorney, Agent, or Firm* — Cascio S. Zervas(57) **CLAIM**

The ornamental design for an alien head massager, as shown and described.

DESCRIPTION

FIG. 1 is a front elevational view of the alien head massager showing my design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The break lines in FIGS. 1-7 are for the purpose of showing indefinite lengths of the rods.
